UNITED STATES PATENT OFFICE.

ERNEST E. ROGERS, OF NEW LONDON, CONNECTICUT.

BOOK-LOCK.

SPECIFICATION forming part of Letters Patent No. 555,829, dated March 3, 1896.

Application filed May 3, 1895. Serial No. 547,969. (No model.)

To all whom it may concern:

Be it known that I, ERNEST E. ROGERS, a citizen of the United States, residing in the city and county of New London, State of Connecticut, have invented certain new and useful Improvements in Book-Locks, which improvements are fully set forth and described in the following specification, reference being had to the accompanying sheet of drawings.

The object of this invention is to provide a simple, strong, cheap and serviceable lock for books, which, while effective when in use, may be removed when no longer needed, and may also be adjusted to and used with books of various sizes.

It is frequently desired to use books of accounts in public places, where the contents of the same are exposed unless provided with some form of protection. Most commonly such books after use are placed in a safe or in a vault until again called into use. My present invention makes it possible to leave such books in exposed places—as, for example, on desks in offices or on counters in stores—with perfect safety.

To assist in the explanation of my invention I have provided the accompanying sheet of drawings, in which—

Figure 1 is a perspective view of a book, showing my improved locking device properly mounted thereon; and Figs. 2, 3 and 4 are enlarged detail views illustrating the construction of my said device.

Referring to the drawings, the letter *a* denotes strips of thin sheet metal, leather or other suitable material, (but preferably sheet metal,) two in number and pivotally secured together at *b*. The strips *a* are caused, when my device is in use in connection with a book, to pass around the same at right angles to each other—that is, one of said strips passes around the book, drawing across the back and front edges thereof, while the companion strip passes around said book, drawing across its top and bottom edges—as readily understood by reference to Fig. 1 of the drawings. When the strips *a* are in the positions relatively to each other just described, the ends thereof are so secured together as to prevent their displacement on the book, and it will be read-

ily understood that when thus secured any attempt to open the book would be futile.

To secure together the free ends of the strips *a*, I have provided what I here term a "shoe" 55 *c*, having each end thereof upturned, as at *c'*, in each of which upturned portions is provided an opening *c*². Midway the length of shoe *c* is a projection or staple *c*³ for a purpose to be explained.

Shoe *c* is fixedly secured to one end of one of the strips *a* by riveting, as in Fig. 2, or in any practicable manner, (said strip being passed through one of the openings *c*²,) and the free end of said strip and also the ends 65 of the companion strip are all provided with openings *a'*, located at stated distances apart in each of said ends, said openings corresponding in shape to the projection *c*³. The projection *c*³ preferably extends in a direction at 70 an angle of forty-five degrees to the general direction of the shoe *c*, and the openings *a'* designed to coat therewith are located at a corresponding angle in the strips *a*. When thus constructed it will be seen that the several perforated ends of strips *a* present a uniform appearance, as shown in Fig. 2 of the drawings.

When it is desired to use my device in connection with a book, the pivoted portion of 80 strips *a* is first placed against one side thereof, and said strips are then passed around the book at right angles to each other, as already explained. Strips *a* are drawn as tightly as possible, and then the free ends provided with 85 the openings *a'* are passed successively over the projection *c*³, said projection *c*³ entering that opening *a'* in each of the ends of strips *a* which has been drawn coincident with said projection. The free end of strip *a* bearing 90 shoe *c*, after being passed around the book, is introduced to the projection *c*³ through the opening *c*², as clearly shown in Fig. 1 of the drawings, and should there be an overlapping end of said strip beyond projection *c*³ said 95 end, if of sufficient length, may be passed through the companion opening *c*² to that last mentioned, said opening serving to prevent loose play of said end.

To prevent the removal of strips *a* from 100 projection *c*³, an ordinary padlock *d* may be employed, as shown in the drawings, the bow

thereof being passed through a hole c^4 in said projection and then locked, after which the strips cannot be removed from the projection until the said lock has been removed. A 5 chain e may also be provided, whereby the lock is secured to the shoe c .

I have already stated that the strips a are pivotally secured together; thus making it possible, when the device is not in use, to 10 swing the strips a parallel after which the complete device can then be rolled into a very small compass.

While I have shown and described the shoe c , it will be apparent that this feature could 15 be dispensed with, as the projection c^3 could be as well secured directly to one of the strips a and the device be equally operative. The particular advantage in employing the shoe c lies in the fact that by means of the up- 20 turned ends thereof, through which one of the strips a passes, it provides bearings for said strip at points somewhat distant from the projection c^3 , and thus endwise movement of the strip is prevented. It will also 25 be seen that a double form of shoe could be provided, shaped substantially like a cross, and thus sidewise play of both strips prevented. The lock d could also have substituted therefor other forms of fastening de-

vices, as, for example, a lock operated by 30 means of a combination, in which case no key would be needed.

Any possible sidewise movement of the strips a may be done away with by making 35 said strips of considerable width, it being apparent that when the device is locked in position upon a book the greater the width of said strips the less will be the liability of their endwise displacement thereon.

My device as a whole may be very cheaply 40 produced, is of neat appearance, of very simple construction, and performs in a very satisfactory manner the work for which it is designed.

Having thus described my invention, I 45 claim—

In combination, in a book-lock, two flexible bands pivotally secured together at approximately midway their length, the ends of said bands being passed around said book 50 and connected by a staple secured to a shoe having guide portions $c' c^2$, substantially as set forth, and a padlock secured to said staple.

ERNEST E. ROGERS.
